Patented Oct. 11, 1955

175,784

FISHING LINE SINKER

Ralph E. Lawrence, Sacramento, Calif., assignor to
Raldon Manufacturing Company, Sacramento, Calif., a
partnership

Application September 24, 1954, Serial No. 32,432

Term of patent 14 years

(Cl. D31—4)

Fig. 1

Fig. 3

Fig. 2

Fig. 1 is a perspective view of a fishing line sinker looking at one side thereof, and showing my new design; the opposite side of the sinker presenting the same appearance.

Fig. 2 is an edge elevation of the sinker.

Fig. 3 is a top plan view of the sinker.

I claim:

The ornamental design for a fishing line sinker, as shown and described.
